C. R. SHORT,
MOTOR VEHICLE,
APPLICATION FILED APR. 6, 1917.

1,335,989.

Patented Apr. 6, 1920.

UNITED STATES PATENT OFFICE.

CHARLES R. SHORT, OF DETROIT, MICHIGAN, ASSIGNOR TO GENERAL MOTORS COMPANY, OF DETROIT, MICHIGAN, A CORPORATION OF NEW JERSEY.

MOTOR-VEHICLE.

1,335,989.

Specification of Letters Patent.

Patented Apr. 6, 1920.

Application filed April 6, 1917. Serial No. 160,133.

To all whom it may concern:

Be it known that I, CHARLES R. SHORT, a subject of the King of Great Britain, and resident of Detroit, Wayne county, State of Michigan, have invented certain new and useful Improvements in Motor-Vehicles, of which the following is a specification.

This invention relates to hydrocarbon motors and particularly to an improved arrangement and disposition of its various parts, which results in a very simple and comparatively inexpensive and compact assembly.

One of the objects of this invention is to provide a novel and improved mounting of the circulating device of a motor cooling system, in proximity to the cylinder jackets.

Another object of this invention is to provide a single mounting for the cooling medium pump and the cooling fan, which is adapted to be detachably arranged on the motor cylinder jacket.

Another object of this invention is to provide an improved assembly and mounting for the motor cooling medium pump and the motor cooling fan.

These, and other objects, will more clearly appear from the following description taken in connection with the drawings which form a part of this specification, and in which:

Figure 1 is a fragmentary side elevation of the front part of a power plant, embodying a form of my invention, with certain portions broken away for the sake of clearness.

Fig. 2 is a fragmentary front elevation of a cylinder, showing a jacket inlet port along the line 2 of Fig. 1; and

Fig. 3 is a detail of a pump impeller.

Referring to the drawings, 10 represents a motor crank case on which may be suitably mounted a multi-cylinder block 11, provided with the usual cooling medium jacket 12. A crank shaft 13 may be mounted in the crank case and provided, adjacent its forward end, with a suitably secured driving pulley 14.

A pump chamber 15 having an inlet port 16 and an outlet port 17, may be detachably mounted, as by bolts 18, on the front end of the cylinder jacket 12.

The usual radiator 19, may be suitably mounted with a conduit 20 connecting its outlet port with the inlet port 16 of the pump chamber, and with a connection 21

leading from the jacket outlet port to the inlet port of the radiator.

The pump chamber is provided with a sleeve or journal 22, and bushing 23, in which the intermediate portion of a shaft 24 is mounted. A suitable packing joint 25 is arranged between the outer portion of the shaft 24 and the journal portion 22 of the pump chamber. And an impeller 26 is adapted to be suitably secured to the inner portion of this shaft.

A fan 27 and a driven pulley 28 may have a pressed fit on the splined portion 29 of the outer end of the shaft 24. And a suitable belt 30 may connect the driving pulley 14 with the driven pulley 28 for driving both the cooling fan and the pump impeller 26.

The jacket inlet opening 31 is provided with an inwardly extending integral flange 32 curved or arcuate in form and concentric with the axis of rotation of the shaft 24 and which flange extends almost entirely around the entire circumference of the opening, forming a baffle for preventing the impeller 26 of the pump from throwing the cooling medium directly against the wall 33 of the adjacent cylinder. Thus is prevented undue cooling of this portion of the cylinder wall and causing a more uniform cooling of the motor cylinders.

It is also to be noted that a boss 34 may be formed on the cylinder wall 33 for supporting the inner end 35 of the shaft 24.

While I have described and will specifically claim what I deem to be a preferred form of my invention, it will be obvious to those skilled in the art, that various modifications and changes may be made without departing from the spirit and scope hereof.

Having thus described my invention, what I claim and desire to secure by Letters Patent, is:

1. In an internal combustion engine, the combination with a cylinder jacket having an opening therein, of a pump casing secured to said jacket, a shaft rotatable in a bearing in said casing, a pump impeller mounted upon said shaft and adjacent said opening, and a baffle arcuate in form and concentric with the axis of said shaft, and arranged intermediate said impeller and the adjacent cylinder wall.

2. In an internal combustion engine, the combination with a cylinder jacket, a cooling medium circulating pump mounted

- thereon adjacent one of the cylinder walls and having a shaft and an impeller for said pump, of a baffle plate arranged between said impeller and said cylinder wall for preventing the cooling medium from being thrown from said impeller directly against said cylinder wall, and a boss formed on said cylinder wall and with which the end of the said pump shaft engages.
3. In an internal combustion engine, the combination with a cylinder and a jacket thereabout, of a pump chamber detachably secured to said jacket, and a shaft having an impeller, one end of which shaft is supported from the cylinder and the other end of which is supported on said chamber.
4. In an internal combustion engine, the

combination with a cylinder and a jacket thereabout, a radiator and a pump and connections for circulating the cooling medium through said jacket, of a shaft supporting said pump and suitably journaled in said jacket and a support from said cylinder, and a cooling fan mounted on said shaft.

5. In an internal combustion engine, the combination with a cylinder and a jacket thereabout, a pump chamber mounted on said jacket, of a shaft in said chamber supported at the inner end thereof from said cylinder, and a pump impeller and a cooling fan on said shaft.

In testimony whereof I affix my signature.

CHARLES R. SHORT.
